CARBONATING AND COOLING MEANS

Leslie Arnett, Chicago, Ill., assignor to Square Manufacturing Company, a corporation of Illinois

Application August 8, 1946, Serial No. 689,284

4 Claims. (Cl. 261—11)

1

This invention relates to carbonating and cooling means, and more particularly to a unitary carbonator-cooler designed for use in an automatic drink vending machine, as for example a machine of the character shown in my copending applications Serial No. D.132,288 filed August 5, 1946, now Design Patent No. 150,916, issued September 14, 1948; and Serial No. 693,428, filed August 28, 1946, and Serial No. 762,107, filed July 19, 1947.

In the preparation and dispensing of many drinks a flavoring syrup or extract is mixed with carbonated water, and drink dispensing machines designed to dispense conventional soft drinks, as for example Coca-Cola, root beer and the like, must have a source of carbonated water. In order to economically and efficiently dispense a large number of drinks rapidly water from the standard local supply is usually carbonated and cooled in the machine, and it is to means for doing this that the present invention is directed.

Previous carbonating and cooling means used in drink dispensing machines had certain defects and disadvantages. Most of them did not provide sufficient reserve capacity, so that a "run" on the machine soon resulted in delivery of improperly cooled and carbonated drinks. In other cases it was necessary to use precooling means in advance of the carbonator, even though some cooling was done in the carbonator. Moreover, carbonators heretofore in use, at least in so far as they are known to me, did not make efficient use of the carbon dioxide gas, or carbonate the water to the maximum extent possible.

I have devised and am here disclosing and claiming an improved carbonator-cooler overcoming these and other disadvantages of prior art devices. My unit comprises a generally cylindrical vertical tank with cooling means arranged around its outer wall and with inwardly extending fins on its inner wall providing the maximum heat transfer relationship with the water being carbonated. The carbon dioxide gas is delivered to a point near the bottom of the unit and so distributed that it bubbles up through the water over a substantial area, upward movement of the bubbles being retarded to provide the maximum length of time of contact with the water. Water entering the carbonator is pumped through an induction or injector nozzle mixing gas with the water in the nozzle, the stream leaving the nozzle being directed against a baffle to cause splashing and formation of small droplets in a gas space, causing further absorption of carbon dioxide gas. The efficiency of the arrangement results in absorbing a much greater amount of carbon dioxide gas in the water than has heretofore been customary; and the considerable quantity of liquid in the carbonator-cooler, together with the fact that it is always drawn off from a point where

the water has had the maximum cooling and carbonation, supplements the efficient continuous cooling and carbonation operation of the unit and provides a good reserve and satisfactory operation even under periods of heavy use of the machine, as in a theater lobby when crowds are leaving at the conclusion of a show.

The foregoing and other features and advantages will be apparent from the following specification and the drawings, in which:

Figure 1 is for a vertical sectional view of carbonating and cooling means embodying my invention; Figure 2 is a horizontal sectional view along the line 2—2 of Figure 1; Figure 3 is a bottom view of the device shown in Figure 1; Figure 4 is a fragmentary enlarged sectional view of the induction nozzle, along the line 4—4 of Figure 1; and Figure 5 is a transverse sectional view of the nozzle along the line 5—5 of Figure 4.

In the particular embodiment of my invention illustrated in the accompanying drawings the main body of the unit comprises a cylindrical shell here identified as 10, this shell being about 27 inches high and 10 inches in diameter in one unit which I have built and found very satisfactory. The bottom is provided with a closure member 11, arched inwardly to better withstand the operating pressures of the order of 90 or 100 pounds per square inch which exist in the carbonator; and the other end is closed by a downwardly arched head member 12, which may be removably sealed in place as by being placed on the top flange 10a of the shell and sealed in place by use of a gasket 14 and bolts 15 clamping mounting rings 13a and 13b together. The result is a closed vessel or chamber capable of withstanding the operating pressure with a considerable margin of safety, and having a substantial capacity for water.

Cooling of the contents of the unit is achieved by use of a helical coil of refrigerating tubing 16, this tubing being adapted to have one end, as the end 16b, attached to the intake of the compressor of a conventional refrigerating unit, as commonly used in drink vending machines, and the other end, as the end 16a, connected to the receiver of such a unit to have liquified refrigerant delivered thereto. The tubing is preferably welded or brazed to the outer wall of the tank 10, and in good heat exchange relationship therewith. In order to provide efficient heat transfer between the refrigerating tubing and the contents of the unit I provide fin members extending generally radially well into the unit. Referring more particularly to Figure 2, the fin members will be seen to comprise a number of identical channel-like members which are U-shaped in horizontal cross section, each such member, as the member 17, having a portion 17a welded or otherwise permanently attached to the inner wall of the shell 10 and inwardly projecting leg portions 17b and

17c. These U-shaped fin members or channel members are of substantial length, as may be best seen in Figure 1 and since they are all substantially identical it is deemed unnecessary to further identify or describe them. The vertical arrangement of these fins permits the cooler water to work toward the bottom of the tank, and the open inner ends of the U-shaped arrangement enables local circulation or eddy currents by the upward movement of the carbon dioxide bubbles, to insure contact of all of the water with such bubbles.

Near the bottom of the tank, as may be best seen in Figure 1, I provide a dome member 18 having a diameter approximately half that of the shell and coaxial therewith, the cross section of this particular dome member being circular. Fastened to the dome member and rising vertically therefrom, and having a circular cross section substantially identical with that of the dome member, is a tube or cylinder of screening, here identified as 19. This screening (and all other metal parts with which the carbonated water comes in contact) is preferably of stainless steel and of relatively small mesh, as about 60 openings to the inch. Carbon dioxide gas from a regular commercial cylinder of such gas is passed through a reducing valve in conventional manner to reduce the pressure to the desired operating level (as for example 90 pounds per square inch gauge pressure) and then delivered through a gas delivery tube 20 passing through the bottom member 11 and terminating under the dome member 18 and at a level of about a half inch above the lower edge of the depending flange 18a at the edge of the dome. Whenever pressure in the tank drops below the pressure in the gas delivery conduit 20, as by continued absorption of the gas in the water or by withdrawal of the carbonated water from the draw-off or outlet conduit 21 near the bottom of the shell during dispensing of drinks, additional gas enters the tank through the conduit 20 and distributes itself around the entire area of the dome 18, bubbling up around the entire periphery of such dome member. This arrangement results in the distribution of the gas bubbles over a large area or periphery line, rather than their coming straight up the center of the tank in large bubbles. The bubbles of gas starting up from the edge of the dome cling to the screening 19 and work up slowly therealong, the screening serving to retard considerably the upward movement of the bubbles and to reduce their size, thus resulting in greater absorption of the carbon dioxide gas in the water before the bubbles reach the top and break through the surface of the water, indicated by the line 22. The ability of water to absorb carbon dioxide gas is increased by reduction in temperature of the water, and accordingly the water in the tank, already initially carbonated in a manner to be described immediately hereafter, absorbs still further gas from the slowly rising bubbles, particularly near the bottom of the tank where the water is coolest. The upward movement of the bubbles also serves to create gentle local circulations or eddy currents in the water which improves the efficiency of both the carbonation and of the cooling by bringing water out near the shell in toward the screen and vice versa.

Water is delivered to the unit through the nozzle 23 in a manner conventional in drink dispensing machines, by an electric pump adapted to provide pressures in excess of the operating pressure in the tank (as for example 10 or 15

10 pounds higher, or in the neighborhood of the 100 pounds pressure in the example given), water being pumped to the nozzle when required through the conduit 24. Control of the water delivery (i. e., starting and stopping of the pump) can be effected in any conventional manner in accordance with the level of water in the tank, the control means being here shown as comprising electrodes 25 and 26, the lower end of the electrode 26, here identified as 26a preferably being of carbon to prevent electrolytic action. These electrodes are connected in a conventional manner to two relays in the control circuit of the pump motor. The arrangement is such that as long as there is relay actuating current flowing from the electrode 26 to ground the pump remains off, but as soon as the water level drops below the end of the electrode 26 the pump is started and runs until the water contacts the electrode 25 to complete a circuit from it to ground and actuate a relay opening the circuit to the pump motor. This arrangement maintains the water level within the tank within predetermined limits, the level never dropping below 25 the bottom of the longest electrode 26 nor rising above the bottom of the shorter electrode 25. The conduits 20 and 24 preferably incorporate check valves (not shown, being conventional) to prevent any outward movement of fluid therethrough.

When sufficient water has been drawn off to drop the level in the tank below the bottom of the electrode 26 starting of the pump forces water through the conduit 24 to the nozzle 23. This nozzle has a delivery opening 23a, as may be best seen in Figure 4, and a plurality of radial gas entry openings 23b-i, these openings entering the central flow channel at the point where the restricted passageway 23k opens into an enlarged section. The vacuum effect produced by Venturi action at this point causes an induction or drawing in of gas to mix it with the water leaving the nozzle, so that the stream delivered from the opening 23a comprises a mixture of water and gas. As may be readily seen in Figure 1, the nozzle is well above the highest level ever reached by water in the tank, so that it is always in a gas space or atmosphere.

Mounted on and carried by the stem or neck 50 of the nozzle 23 is a baffle member 21 having an upper portion 21a welded or otherwise permanently attached to such stem, a depending portion 21b, and a lower horizontal portion 21c. This lower portion 21c is above the maximum level of water in the tank, and is arranged below 55 and in line with the stream of fluid leaving the opening 23a of the nozzle, so that the stream strikes this baffle portion at right angles to its surface and scatters the water in a spray of droplets which travel through the gas in the space above the water for further gas absorption. The depending portion 21b is designed to protect the electrodes 25 and 26 and the thermostat well 28 (housing the bulb of the thermostat 60 controlling the refrigerating unit) from being affected by the spray of water droplets when water is being pumped into the tank.

As will be apparent from the foregoing, the device just described provides three actions tending to facilitate adsorption of carbon dioxide gas by the water being carbonated. The first of these is the admixture of gas and water which takes place in the induction or injector nozzle. The second is the dividing of the entering stream 65 of water into a spray of fine droplets, which

travel through the gas for further absorption, by causing the stream to strike the baffle portion 27c. The final stage in the absorption operation is effected by the slow upward movement of small bubbles of gas through the body of liquid in the tank as the same is being cooled. Moreover, it will be seen that a very effective heat transfer arrangement is provided for maximum cooling of the water in the tank; and that the arrangement is such that the water drawn off from the tank is always that which has been cooled and carbonated to the maximum extent. The size of the tank is such that it provides a reservoir of sufficient carbonated water for about 150 drinks of the size usually dispensed for a nickel, providing a reserve helping the carbonator-cooler unit carry the load when a large number of drinks are being dispensed in rapid succession, this reserve capacity and the continuous operation capacity of the unit being sufficient to enable two or three times that number of drinks to be dispensed before the temperature of the drink becomes undesirably high and the carbonation unsatisfactorily low. This is of particular importance in an automatic drink dispensing machine of the kind used in theater lobbies, where two thousand drinks a day or more may be dispensed from a machine served by my carbonator-cooler, and where there are heavy "runs" at certain periods. Moreover, the unit disclosed and claimed here is simple and rugged, in addition to being highly efficient, and is self-contained, no precoolers or the like being necessary.

While I have shown and described certain embodiments of my invention it is to be understood that it is capable of many modifications. Changes, therefore, in the construction and arrangement may be made without departing from the spirit and scope of the invention as disclosed in the appended claims.

I claim:

1. Carbonating and cooling means of the character described, including: a vessel providing a closed chamber; means for delivering the liquid to be carbonated to said vessel under pressure and for maintaining the liquid level therein within predetermined limits to provide a gas space thereabove, said means including an induction nozzle in said space; means for cooling said liquid; a gas conduit entering said vessel and terminating at a point near the bottom of said chamber, said conduit being adapted to be connected to a source of carbon dioxide gas under pressure to deliver gas to the chamber; a dome member in the chamber immediately above the point of delivery of gas thereto, whereby gas entering said chamber is distributed around the periphery of said dome member and bubbles up therefrom; and screen tubing immediately above said dome member and having a cross-section substantially identical therewith, said screen retarding the upward movement of the bubbles through the liquid.

2. Carbonating and cooling means of the character described, including: a generally cylindrical vessel providing a closed chamber and arranged with its axis vertical; fin members projecting inwardly from the inner cylindrical wall of said vessel; cooling means comprising a helical conduit in heat exchange relation with the outer cylindrical wall of said vessel; an induction nozzle in the upper part of said vessel; means for delivering the liquid to be carbonated to said nozzle under pressure; means for controlling the

liquid delivery means for maintaining the liquid level in the chamber within predetermined limits, the maximum level being below said nozzle; liquid draw-off means near the bottom of said chamber; a gas conduit entering said vessel and terminating at a point near the bottom of said chamber, said conduit being adapted to be connected to a source of carbon dioxide gas under pressure to deliver gas to the chamber; a dome member in the chamber immediately above the point of delivery of gas thereto, whereby gas entering said chamber is distributed around the periphery of said dome member and bubbles up therefrom; and screen tubing immediately above said dome member and having a cross-section substantially identical therewith, said screen retarding the upward movement of the bubbles through the liquid.

3. Apparatus of the character claimed in claim 2, including baffle means against which the liquid leaving said nozzle strikes, the baffle means being above the maximum level of liquid in the chamber.

4. Carbonating and cooling apparatus of the character described, including: a generally cylindrical vessel providing a closed chamber and arranged with its axis vertical; fin members projecting into said chamber from the inner cylindrical wall of said vessel; cooling means comprising a helical conduit in heat exchange relation with the outer cylindrical wall of said vessel; an induction liquid inlet nozzle in the upper part of said vessel; means for delivering the liquid to be carbonated to said nozzle under pressure; at least one electrode in said chamber for controlling the liquid delivery means for maintaining the liquid level in the chamber within predetermined limits, the maximum level being below said nozzle; liquid draw-off means near the bottom of said chamber; a baffle in said chamber having a portion against which the liquid leaving said nozzle strikes and a portion protecting said electrode means from spray; a gas conduit entering said vessel and terminating at a point near the bottom of said chamber, said conduit being adapted to be connected to a source of carbon dioxide gas under pressure to deliver gas to the chamber; a dome member in the chamber immediately above the point of delivery of gas thereto, whereby gas entering said chamber is distributed around the periphery of said dome member and bubbles up therefrom; and screen tubing immediately above said dome member and having a cross-section substantially identical therewith, said fins extending inwardly substantially to said screen, the axis of said tubing being vertical and said screen retarding the upward movement of the bubbles through the liquid.

60 LESLIE ARNETT.
